UNITED STATES PATENT OFFICE.

MATHEW S. KELLY, OF ST. PAUL, MINNESOTA.

STOCK AND DRIVE GATE.

Application filed April 27, 1921. Serial No. 465,066.

To all whom it may concern:

Be it known that I, MATHEW S. KELLY, a citizen of the United States, residing at St. Paul, in the county of Ramsey and State 5 of Minnesota, have invented a new and useful Stock and Drive Gate, of which the following is a specification.

My invention relates to stock and drive gates and has for its object to provide a gate 10 having a pair of supporting posts, arranged to support two swinging gates in slidable relation thereon, so that the said gates may be lifted vertically to permit passage through the same or for swinging outwardly upon 15 their hinges as required.

Another object is to provide a pulley at each of the upper ends of the gate posts, with a cord secured at one end of said gate and at the other end to a counter weight 20 passing over, thus supporting the gate in either closed or elevated position.

A still further object is to provide a guide way with an auxiliary member slidable with the said guide way, to which the gate is 25 attached.

A still further object is to provide means for holding the gate locked in either its open or closed position.

The full objects and advantages of my 30 invention will appear in connection with the detailed description thereof, and are particularly pointed out in the claims.

In the drawings, the figure is a perspective view of my invention.

The invention proper consists of two gate posts 10 and 11 which may be secured to the ground or to the structure with which they are used in conjunction, in any suitable manner. These two posts are connected together 40 at the top by means of two rails 12 and 13 which are rigidly secured to the upper ends of the same. By means of these rails the posts 10 and 11 are held in spaced relation to one another, to support the gate structure 45 of the invention.

The gates proper are indicated in their entirety at A and B. Each consists of upper and lower rails 14 and 15 and stiles 16 and 50 17 which are connected thereto and which may be braced with a diagonal brace 18 if desired. The entire structure is nailed together in the usual manner to secure a substantial structure which is attached to and extends between the two gate posts 10 and 11. 55 Although I have shown the gates to be con-

structed of wood, the same may be constructed of other material if desired.

For operating the gates, I attach to each of the posts 10 and 11, two strips 19 and 20 which are formed with oppositely facing grooves 2, for providing guide ways along each of said posts. Within said guide ways are slidably mounted two tongued supporting members 1, whose tongues set within the grooves 2 to retain the same in place. These members 1 are of a length substantially equal to the height of the gates A and B and are provided with hinges 21 by means of which the said gates may be hinged thereto. To the upper end of each of the members 1, is attached a rope 3, which rope extends upwardly between the strips 19 and 20 and over a pulley 22, journaled in the upper end of each of the posts 10 and 11 and has attached to its other end a counter weight 75 23 equal to the weight of either of the gates A or B. By grasping either of the gates A or B and lifting the same, the members are caused to slide within the guides formed between the strips 19 and 20 so that the gate 80 may be raised above the level of the ground to permit passage beneath the same. As can be readily seen, each of the gates may be independently raised or lowered to give access beneath the same, or either of the gates may 85 be swung on the hinges to permit passing through the device.

For holding the gate closed from swinging, I provide a latch bar 4 which is pivoted to the gate B at 24 and which is adapted to 90 rest in a number of keepers 5 attached to the two gates. A pin 6, insertable in one of the said gates, immediately above the latch bar 4 prevents accidental removal of the said latch bar from the keepers 5. For holding the members 1 in elevated or lowered position, I provide a pair of bolts 7 which are slidably mounted in said members and are adapted to pass through the same and into the posts 10 and 11. These bolts have 95 attached to them rods 8 which are pivoted to levers 25 which levers are in turn pivoted to the respective gates. When the said levers are moved in one direction the bolts are withdrawn from engagement with the posts 105 10 and 11 and when the said levers are moved in the opposite direction members 1 are held fast to the said posts.

The advantages of my invention are manifest. In stock yards or similar places where 110

22

animals have to pass through the gates, the animals crowd up to the same, so that it is absolutely impossible to swing the gates open to permit passage therethrough without backing up the animals. My invention 5 eliminates this disadvantage, in that the gate may be raised upwardly so that the same does not interfere with the animals as they may be located prior to passing through 10 the gate. When used as a driving gate, the device saves a great number of steps to the person using the gate, as the vehicle may be stopped much closer to the gate than would be possible, were the gate simply swung in 15 the usual manner. It may further be stated that when it is desired to permit a pedestrian to pass through the gate, the same may be opened and swung outwardly an amount sufficient to permit of the passage of a person 20 through the same, instead of raising the entire gate. In addition to the above features of the invention, the gates may be independently raised and lowered so that a portion 25 of the full opening of the gate may be secured.

In accordance with the patent statutes I have described the principles of operation of my invention, together with the apparatus which I now consider to represent the best embodiment thereof, but I desire to 30 have it understood that the construction shown is only illustrative and that the invention can be carried out by other means and applied to uses other than those above set forth within the scope of the following 35 claim.

I claim:

A gate closure comprising a gate post, a pair of oppositely facing grooved guideways secured to said post, a tongued upright 40 slideable between said guideways, a gate hingedly connected to said upright, said post being formed with a recess at its upper end, a pulley positioned within said recess extending beyond said post on both sides 45 thereof, a cord passing over said pulley and secured at one end to said upright and a counter weight secured to the other end of said cord.

MATH. S. KELLY.
